UNITED STATES PATENT OFFICE.

CORNELIUS C. HASTINGS, OF SPRINGFIELD, MASSACHUSETTS, ASSIGNOR TO MILTON-BRADLEY COMPANY, OF SPRINGFIELD, MASSACHUSETTS, A CORPORATION OF MASSACHUSETTS.

PAPER-CUTTER.

1,123,191.

Specification of Letters Patent. Patented Dec. 29, 1914.

Application filed February 3, 1912. Serial No. 675,304.

To all whom it may concern:

Be it known that I, CORNELIUS C. HASTINGS, a citizen of the United States of America, residing at Springfield, in the county of 5 Hampden and State of Massachusetts, have invented new and useful Improvements in Paper-Cutters, of which the following is a specification.

This invention relates to an improvement 10 in paper cutting machines. Such machines are generally arranged so that the knife, in cutting any stock, has to be both raised and lowered by the operator who estimates the extent of elevation of the knife necessary for 15 the stock being cut.

This invention has for its object to provide means for automatically raising the knife, with respect to the cutter-board of such machine, just the right amount for the 20 stock being cut immediately after the knife has been lowered.

In the drawings forming part of this application,—Figure 1 is a plan view of a paper cutter embodying the invention, a 25 part thereof shown in section to better disclose said part. Fig. 2 is a side view of the same.

In the drawings forming part of this application,—*c* represents the table of a paper-cutter. The knife *b* with the handle *a* is pivoted on one side of the table and fixed on the shaft *i* which is rotatably mounted in the casting *m* on the side of the frame. The knife is held against the side of the cutter-board by means of the spring *h* which has one end fastened to the casting *m* and the other end fastened to a nut *g* which engages a screw-thread on the shaft *i*. As the nut *g* is turned toward or away from the casting, it will put the spring *h* more or less under torsional stress accordingly.

It will be seen that if the nut *g* is held from turning on the screw-thread on the shaft *i* while the spring is under stress, said 45 spring will operate to turn the shaft *i* through the nut *g* and relieve the stress. This operation is used in raising the knife

b after a cutting operation. The knife *b* is raised more or less according to the amount of stress which is put on the spring *h*. The 50 nut *g* is used to regulate the amount of stress of the spring *h* by movement toward or away from the casting on the frame, and after the stress has been thus regulated the lock-nut *f* is used to fix the nut *g* in its adjust- 55 ed position. This lock-nut or jam-nut *f* operates on a smaller pitched thread *e*, as shown in Fig. 1, and thus efficiently jams against the nut *g* for the desired purpose.

Referring to Fig. 2, when it is desired to 60 cut paper or other stock of comparatively small area, it is only necessary to raise the knife *b* a small distance, as shown in this figure. The apparatus is regulated by adjusting the spring *h* to the desired degree 65 to raise the knife *b*, as shown in Fig. 2. The stock may then be cut and after each cutting operation the knife is automatically turned to its original position by the spring, as described. When it is desired to cut 70 stock of a larger size, the spring *h* is regulated by the nuts *g* and *f* to raise the knife *b* to the required extent and then the operation is the same, for the spring will raise the 75 knife to its original position after that position has been determined by the adjustment of the devices mentioned.

A cutter which, broadly, will operate the same as the one herein described is set forth and claimed in my copending application 80 for Letters Patent of the United States filed Feb. 3, 1912, under Serial No. 675,303. The specific construction herein disclosed however has certain advantages in some lines 85 of work over that described in my co-pending application.

What I claim, is:—

1. In combination with the bed-plate of a paper-cutter, a bearing rigid with said bed-plate, a shaft revoluble in said bearing and 90 having a screw-threaded portion, and a reduced end adjacent thereto, said end lying on the shear side of the knife, a spiral spring having one end secured to the bearing and

the other to a nut on said screw-threaded portion, a jam-nut for said nut, and a knife rigid with said shaft.

2. In a paper-cutter, including a knife, a bearing, a revoluble shaft therefor having a threaded portion, said threaded portion lying on the shear side of the knife, a spiral spring having its ends secured, respectively,

to the bearing and a nut on said threaded portion, and tension-adjusting means for said spring including a jam-nut for said first-mentioned nut.

CORNELIUS C. HASTINGS.
